US00D861248S

(12) **United States Design Patent** (10) **Patent No.:** **US D861,248 S**
Barbaglia et al. (45) **Date of Patent:** **** Sep. 24, 2019**

(54) **DEPILATORY DEVICE**

(71) Applicant: **Reckitt Benckiser (Brands) Limited**, Slough (GB)

(72) Inventors: **Laura Barbaglia**, Parsippany, NJ (US); **Samuel James Roper**, Hull (GB); **Xian Zhi Zhou**, Dongguan (CN)

(73) Assignee: **RECKITT BENCKISER HEALTH LIMITED**, Slough (GB)

(**) Term: **15 Years**

(21) Appl. No.: **29/611,921**

(22) Filed: **Jul. 26, 2017**

(30) **Foreign Application Priority Data**

Feb. 21, 2017 (EM) 003760917-0002

(51) **LOC (12) Cl.** **28-03**

(52) **U.S. Cl.** **D28/44.1**
USPC **D28/44.1**

(58) **Field of Classification Search**

(57) **CLAIM**

The ornamental design for a depilatory device, as shown and described.

DESCRIPTION

FIG. 1 is a front, right perspective view of our new design for a depilatory device;

FIG. 2 is a front elevation view thereof;

FIG. 3 is a left side elevation view thereof;

FIG. 4 is a back elevation view thereof;

FIG. 5 is a right side elevation view thereof;

FIG. 6 is a top plan view thereof; and,

FIG. 7 is a bottom plan view thereof.

The broken lines are included for the purpose of illustrating a portion of the depilatory device which form no part of the claimed design.

1 Claim, 7 Drawing Sheets
